UNITED STATES PATENT OFFICE

2,626,346

FLUORESCENT LIGHT FIXTURE FOR
CIRCULAR FLUORESCENT LAMPS

Warren H. Stoller, Chicago, Ill.

Application January 26, 1949, Serial No. 72,803

6 Claims. (Cl. 240—51.12)

1

This invention relates to a fluorescent light and concerns itself with a device involving a circular fluorescent tube with means mounted concentric of the tube or within the confines of the same for reflecting light rays emitted from the inner surface of the tube and in which the device is provided with an externally accessible socket for the attachment of an electrical appliance which it may be desired to operate without disconnecting the light.

According to this invention, a better distribution of light is obtained through the reflecting means within the circle of the fluorescent tube which reflects the light rays at various angles to all parts of the room or space where the light may be.

In addition, the external socket on the device permits the attachment of an electric appliance which it is desired to operate without disconnecting the light from its socket. In buildings or dwellings where there may be an insufficient number of wall sockets for electric appliances or where there may be only one socket, the feature involving the external socket is especially desirable.

The invention comprises the novel structure and combination of parts hereinafter described and more particularly pointed out and defined in the appended claims.

In the accompanying drawing which illustrates a preferred form of this invention and in which similar reference numerals refer to similar features in the different views:

Fig. 1 is an elevational view of a fluorescent light involving this invention;

Fig. 2 is a horizontal sectional view taken upon the line 2—2 of Fig. 1;

Fig. 3 is a sectional view taken substantially upon the line 3—3 of Fig. 2;

Fig. 4 is an enlarged fragmentary sectional view illustrating certain features;

Fig. 5 is a detail elevational view taken along the line 5—5 of Fig. 4;

Fig. 6 is a disassembled view of the different parts shown in elevation.

In referring now to the drawing, there is shown one form of the device as a matter of illustration. This device comprises a casing 7 consisting of two circular conical sections 8 and 9 which are made of transparent plastic or glass or similar products and which are of circular form. At the outer periphery of each section, there is a rim 10 having a curved bearing recess 11 which together form a curved or concave seat for circular fluorescent tube 12. The screen section 8 has

2

three downwardly directed bifurcated lugs 13 having guide ways 14 while the screen section 9 has three upwardly directed lugs 13 with guide ways 14 which are adapted to register with the guide ways 14 in the upper lugs when the parts are in assembled relation.

A reflector 15 is supported in the chamber formed between the two screen sections. This reflector consists of two conical sections 16 and 17 which may be made of polished metal or any other good light reflecting material. The section 16 has an electric current plug 18 extending from its apex for the entrance of a current. The reflector section 17 has three radiating hollow arms 19 which are so spaced as to fit in the guide ways 14 of the lugs for supporting the reflector in said chamber. The two reflector sections are connected together by suitable bolts 20 as shown in Fig. 3.

20 An electric cable 21 which is connected to the plug 18 extends through the reflector 15 and is equipped with an electric socket 22 having a switch 30 which projects through the reflector and screen and is adapted for receiving a plug 23 25 of a power line for operating an electric appliance in the building or dwelling while the light is burning, and thus form a kind of adapter. The end of one arm 19 which is hollow is provided with a plurality of apertures (Fig. 4), designated 24 which are adapted for receiving the prongs extending from the adjacent ends of the tube 12 as shown in Fig. 2. The cable 21 has a branch extending thru the hollow arm 19 and connected to the socket formed by the apertures 24.

30 In Fig. 6, the parts are shown in disassembled relation. To assemble the parts, the reflector sections 16 and 17 are bolted together with the cable 21 within the same. The screen sections 8 and 9 may then be brought together over the reflector with the lugs 13 in proper registry for engaging the arms 19 of the reflector and with the tube 12 therebetween. The screen sections may then be bolted together by screws or bolts 40 45 26. In assembled relation, the plug 18 extends through the apex of the screen section 8 for the connection of a source of current.

In addition, the provision of the socket 22 that will accommodate a power line from an electric 50 appliance increases the usefulness of the device, especially in dwellings or buildings where wall sockets are scarce and have not been installed in sufficient or suitable places.

I am aware that many changes may be made 55 and various details of constructions may be modi-

fied without departing from the principles of this invention so I do not propose limiting the patent granted otherwise than necessitated by the appended claims.

I claim:

1. In a device of the class described, a casing consisting of two transparent conical sections having hollow interiors and abutting bases with peripheral concave bearing recesses, a circular fluorescent tube supported in said recesses, a light reflector consisting of two conical connected sections supported in said casing with the apices thereof positioned in the apices of said casing and adapted for reflecting light emitted from the inner circumference of said tube, means for conducting electrical energy to said tube and means for securing said sections together.

2. In a device of the class described, a casing consisting of two conical transparent mating sections in abutting relation and having a peripheral concave recess, a circular fluorescent tube in said recess, a reflector consisting of two conical sections having opposed apices in said casing and adapted for reflecting light rays emitted from the inner circumference of said tube, means for supporting said reflector within said casing including a tubular member extending from said reflector to said tube and electrical conducting means extending thru said apices into said reflector and thru said hollow member 30 adapted for connection to said tube.

3. In a device of the class described, a circular casing consisting of two conical transparent sections having their bases in abutting relation and a circular bearing recess at the juncture of said sections and upon the periphery of said casing, a circular fluorescent tube supported in said recess, a light reflector consisting of two conical connected sections having opposed apices seated in the apices of said casing and adapted for reflecting light rays emitted from the inner circumference of said tube, and radiating arms connecting said reflector and casing.

4. In a device of the class described, a casing consisting of two transparent conical sections having bases in abutting relation and a circular concave recess in its periphery, a circular fluorescent tube supported in said recess, a light reflector consisting of conical sections supported

in said casing with the apices thereof positioned in the apices of said casing and adapted for reflecting light emitted from the inner circumference of said tube and means for conducting electrical energy thru said reflector and into said tube.

5. In a device of the class described, a casing consisting of two transparent conical mating sections having abutting bases with an annular concave recess in its periphery, a light fluorescent tube in said recess, a light reflector consisting of two conical connected sections in said casing, said reflector having radially extending arms and said casing having lugs supporting said arms, a hollow member connecting said reflector and casing and electrical conducting means extending into said reflector and thru said hollow member to said tube.

6. In a device of the class described, a hollow 20 transparent casing consisting of two conical mating sections in abutting relation and having an annular concave recess at the juncture of said sections, an annular fluorescent tube seated in said recess, a light reflector consisting of two conical connected sections in said casing, co-acting means between said reflector and casing for supporting said reflector centrally of the casing and an electrical cable extending into said reflector and having a connection to said tube.
